UNITED STATES PATENT OFFICE.

JOHN G. FULTON, OF MIDDLEPORT, OHIO.

SALT-PACKING MACHINE.

Specification of Letters Patent No. 11,480, dated August 8, 1854.

To all whom it may concern:

Be it known that I, JOHN G. FULTON, of Middleport, Meigs county, Ohio, have invented a new and useful Machine for Packing Salt; and I do hereby declare the following to be a full, clear, and exact description thereof, reference being had to the annexed drawings, making part of this specification.

10 The object of my invention is to pack salt in barrels by means of "power" instead of by means of hand-mallets as is now done.

In the accompanying drawings Figure 1 is a front elevation. Fig. 2 is a vertical section through one of the stampers and its lifting wheel.

(a) is the base board, to which are affixed a pair of stanchions (b), supporting two cross beams (c, d,) affording guides for the shafts (e) of the stampers (f). These stampers have a conical termination having radial grooves or corrugations (f'). Each stamper shaft is furnished with a rack (g), which meshes into cogs (h), partially surrounding a nave (i). These naves are all fixed to one shaft (m), which shaft is driven by power. The conical form of the stamper head, has the effect of forcing the salt to-

ward the sides of the barrel and is especially useful at the bulge, and the radial grooves 30 confine and compact the salt more effectually than a simple cone would do. The tooth (j) which comes first into play is fixed with a spring so that in case it comes in contact with a tooth instead of a space it may yield 35 rather than break a tooth.

(k) are elevations, which exactly fill the space within the chime and hold the barrel to its place. (l) is a clamp which also assists in confining the barrels. 40

It is evident that whatever be the height of the salt within the barrels, the stampers are lifted the same height above the salt.

I claim herein as new and desire to secure by Letters Patent— 45

1. The conical stampers having radial grooves for the purpose described.

2. The yielding tooth in this connection to enable the commencement of the lifting action, without damage to the teeth. 50

In testimony whereof, I hereunto set my hand before two subscribing witnesses.

JNO. G. FULTON.
